ELECTRON DISCHARGE TUBE

Clarence E. Neat, Gloucester, N. J.

Application April 8, 1952, Serial No. 281,140

5 Claims. (Cl. 313—72)

This invention relates to electron tubes, and more particularly to an improved electron discharge tube having means for controlling the output anode current through the tube.

The main object of the invention is to provide a novel and improved electron discharge tube which is simple in construction, which is compact in size, and which may be employed either to provide negative or positive transconductance characteristics.

A further object of the invention is to provide an improved electron discharge tube which is relatively inexpensive to manufacture, which is rugged in construction, and which may be employed either to provide a reduced voltage output, whereby it may be employed for desired purposes such as volume compression or the like, or may be employed to provide an amplified output having a more linear characteristic than is ordinarily available from a conventional triode.

A further object of the invention is to provide an improved electron discharge tube which may be employed either as a triode to provide amplified output or as a diode providing similar amplification.

Further objects and advantages of the invention will become apparent from the following description and claims, and from the accompanying drawings, wherein:

Figure 1 is a horizontal cross sectional view taken through one form of electron discharge tube constructed in accordance with the present invention.

Figure 2 is a vertical cross sectional view taken through the discharge tube shown in Figure 1 and showing the internal components in side elevation.

Figure 3 is a vertical cross sectional view taken on the line 3—3 of Figure 1.

Figure 4 is a horizontal cross sectional view of another form of improved discharge tube according to the present invention.

Figure 5 is a side elevational view, partly in vertical cross section of the form of tube shown in Figure 4.

Figure 6 is a vertical cross sectional view taken on the line 6—6 of Figure 4.

Figure 7 is a typical wiring diagram showing the improved electron discharge tube connected as a diode in an electrical circuit.

Figure 8 is a typical wiring diagram illustrating an arrangement wherein the improved electron discharge tube of the present invention is employed as a triode.

Referring to the drawings, and more particularly to Figures 1, 2 and 3; one form of improved electron discharge tube according to the present invention is designated generally at 11. The discharge tube comprises a central axially arranged cathode 12 which may contain a suitable filament, not shown, having leads for connecting same to a source of filament current. The discharge tube 11 is provided with an annular cylindrical outer electrode 13 of sheet metal or the like which is arranged concentrically with respect to the cathode 12, said cathode extending axially of the cylindrical electrode 13. The an-

2

nular electrode 13 is sealed in a drum-shaped casing 14 of glass or other suitable insulating material which forms the housing for the discharge tube. Connected to the outer electrode 13 is a lead wire 15.

Designated at 16 is the output anode which is cylindrical in shape and which is arranged concentrically with respect to the cathode 12, said output anode 16 being located inwardly adjacent the outer electrode 13, as shown. Designated at 17 is a flat annular control electrode which is arranged concentrically with respect to the cathode 12 and which is located inwardly of the output anode 16 and which is connected thereto by a plurality of radial connecting bars 18. The bottom edge of the output anode 16 is serrated, as shown at 19, and the serrations are directed away from and are offset from the plane of the annular control electrode 17, as is clearly shown in Figure 3. As shown in Figure 3, the apices of the serrations 19 are directed downwardly away from the plane of the control electrode 17, the control electrode being located substantially in the plane of the top rim of the output anode 16.

Designated at 20, 20 are respective focussing electrodes of annular shape which are supported concentrically around the cathode 12 between said cathode and the control electrode 17, said focussing electrodes 20 being supported on their terminal wires 21, and being arranged to define an annular electron focussing slot 22 located substantially in the radial plane of the output anode 16.

It will be understood that when the cathode 12 is energized and when the anodes 13 and 16 are connected to suitable potential terminals which are positive relative to the cathode 12, electrons from said cathode will be attracted toward the anodes 16 and 13, and if the focussing electrodes 20, 20 are connected to a potential terminal which is positive relative to said cathode, the electrons will be focussed and will assume the form of a flat circular sheet which is concaved toward the control electrode 17 because of the attraction exerted by said control electrode on the electrons, and whose concavity may be varied by varying the magnitude of the positive potential on said control electrode. For example, the device may be connected in the manner shown in Figure 7, wherein the cathode 12 is connected to the negative terminal of a battery 23, having an intermediate grounded cell terminal, shown at 24. Connected to the positive terminal of the battery 23, shown at 25, is the negative terminal of another battery 26 whose positive terminal is connected by a wire 27 to the terminal lead 15 of the outer anode 13.

The focussing electrodes 20, 20 are connected together, as by an external connection 28 and are connected to ground. Designated at 29 is an input device which may be a transducer, such as a microphone, or other variable resistance device, or alternatively may be a signal source. The input device 29 is connected in series with a load resistor 30 between the common terminal 21 of electrodes 16 and 17 and the positive terminal 25 of battery 23. From the circuit of Figure 7, it will be seen that as the potential on the control anode 17 increases, the electron stream, shown at 31, will be deflected upwardly as it moves toward the output anode 16 and will be intercepted by an increasing area of the output anode 16 in view of the triangular shape of the serrations 19. Therefore, a correspondingly increased current will flow in the series circuit including the input device 29 and the load resistor 30, and an amplified potential will appear across the terminals 31, 32 of said load resistor. The linearity of the amplification characteristics of the electron tubes, connected in the manner shown in Figure 3, may be regulated by adjusting the shapes of the serrations 19. By properly designing the serrations 19, almost perfect lin-

earity may be obtained for said amplification characteristics.

In the connections shown in Figure 7, the outer electrode 13 serves to collect the electrons which pass through the output anode 16 and return said electrons to the positive terminal of the battery 26. The outer electrode 13 acts as a high voltage anode to attract the saucer-shaped electron beam and to provide a sufficient acceleration on the electrons of said beam to cause said flat saucer-shaped beam to pass through the notches in the output anode 16.

Referring now to Figures 4, 5 and 6, the output anode, shown at 16', may be arranged with the apices of the serrations 19 directed upwardly, as viewed in Figures 5 and 6, namely toward the plane of the control electrode 17, whereby increase of potential on the control electrode 17 causes a decrease in the number of electrons intercepted by the output anode 16, and consequently causes the current flowing in the series circuit containing the input device 29 and the load resistor 30 to be reduced in accordance with increases in potential on the control electrode 17. This provides a negative transconductance characteristic, inasmuch as the output current in the circuit containing the load resistor 30 is reduced when the resistance of the input device 29 decreases, where said input device is of the variable resistance type, or where the signal voltage provided by said input device increases, as where the input device is a signal source. The electron discharge tube of Figures 4, 5 and 6, may be therefore employed in a circuit, such as shown in Figure 7, to provide a voltage compression effect, such as the signal compression desired in certain types of audio equipment.

The degree of voltage compression, namely, the negative transconductance of the electron discharge tubes may be regulated both by varying the shape of the serrations 19 and by varying the potentials provided by the batteries 23 and 26. In the form of the invention shown in Figures 1, 2 and 3, the amplification factor, as well as the linearity of the characteristics of the tube may be varied by varying said battery voltages.

Referring now to Figure 8, the device may be employed as a triode by providing separate connections for the control electrode 17 and the output anode 16. Instead of employing the radial connection bars 18, as described in the previous forms of the invention, the electrodes 16 and 17 are provided with separate leads extending through the insulating wall of the tube. As shown in Figure 8, the output anode 16 may be connected in series with the load resistor 30 and the control electrode 17 may be connected between the signal input source 29' and ground. This provides substantially a conventional amplifier triode arrangement wherein the control electrode 17 takes the place of the amplifier triode grid and the output anode 16 takes the place of the conventional amplifier triode plate. The device may either be a positive transconductance tube, as shown in Figures 1 to 3, whereby the circuit performs substantially in the same manner as a conventional triode amplifier circuit, or the device may be arranged as shown in Figures 4, 5 and 6, whereby the said circuit exhibits a negative transconductance. The circuit of Figure 8, or a similar circuit employing the device of Figures 4, 5 and 6 may be employed to provide signal compression similar to the signal compression provided in the diode-connected arrangement of the device illustrated in Figure 7.

While certain specific embodiments of an improved electron discharge device have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a vacuum tube of the character described, a cathode, an annular cylindrical outer electrode surrounding and concentric with said cathode, a flat annular control electrode arranged in a radial plane concentric with

said cathode and located between the cathode and the outer electrode, an annular cylindrical output anode arranged concentrically with said cathode between the control electrode and the outer electrode, the major portion of said output anode being spaced axially from said radial plane and having irregular edges arranged so that said output anode will gradually intercept varying quantities of electrons from the cathode in accordance with the potential applied to said control electrode, and conductor means electrically connecting the output anode and said control electrode together, said conductor means being arranged so that exactly the same potential exists on said anode and control electrode.

2. In a vacuum tube of the character described, a substantially rod-like cathode, an annular cylindrical outer electrode surrounding and concentric with said cathode, a flat annular control electrode arranged in a radial plane concentric with said cathode and located between the cathode and the outer electrode, an annular focusing electrode arranged concentrically with said cathode and located between said cathode and the control electrode, an annular cylindrical output anode arranged concentrically with said cathode between the control electrode and the outer electrode, the major portion of said output anode being spaced axially from said radial plane and having serrated edges, the apices of the serrations on said edges being directed toward said radial plane and said serrations being arranged so that said output anode will gradually intercept decreasing quantities of electrons from the cathode in accordance with increases in the potential applied to said control electrode, and conductor means electrically connecting the output anode and said control electrode together, said conductor means being arranged so that exactly the same potential exists on said anode and control electrode, said focusing electrode being provided with an annular electron focusing slot located substantially in the radial plane of the output anode.

3. In a vacuum tube of the character described, a cathode, an annular cylindrical outer electrode surrounding and concentric with said cathode, a flat annular control electrode arranged concentrically with said cathode and located between the cathode and the outer electrode, an annular cylindrical output anode arranged concentrically with said cathode between the control electrode and the outer electrode, and means electrically connecting said control electrode and output anode together to place said control electrode and output anode at the same potential, the major portion of said output anode being spaced axially from said radial plane and having irregular edges and being arranged so that said output anode will gradually intercept varying quantities of electrons from the cathode in accordance with the potential applied to said control electrode and output anode.

4. In a vacuum tube of the character described, a substantially rod-like cathode, an annular cylindrical outer electrode surrounding and concentric with said cathode, a flat annular control electrode arranged concentrically with said cathode and located between the cathode and the outer electrode, an annular cylindrical output anode arranged concentrically with said cathode between the control electrode and the outer electrode, the major portion of said output anode being spaced axially from said radial plane and having serrated edges, and means electrically connecting said control electrode and said output anode together to place said control electrode and output anode at the same potential, said serrated edges being arranged so that said output anode will gradually intercept varying quantities of electrons from the cathode in accordance with the potential applied to said control electrode and output anode.

5. In a vacuum tube of the character described, a cathode, an annular cylindrical outer electrode surrounding and concentric with said cathode, a flat annular control electrode arranged in a radial plane concentric with said

cathode and located between the cathode and the outer electrode, an annular cylindrical output anode arranged concentrically with said cathode between the control electrode and the outer electrode, the major portion of said output anode being spaced axially from said radial plane and having serrated edges, the apices of the serrations on said edges being directed toward said radial plane, and means electrically connecting said control electrode and output anode together to place said control electrode and output anode at the same potential, said serrated edges being arranged so that said output anode will gradually intercept decreasing quantities of electrons from the cathode in accordance with increases in the potential applied to said control electrode and output anode.
